UNITED STATES PATENT OFFICE.

DAVID F. LAING, OF McDONALD HILLS, SASKATCHEWAN, CANADA.

SWINGLETREE-CLIP.

1,353,049.

Specification of Letters Patent. Patented Sept. 14, 1920.

Application filed November 27, 1918. Serial No. 264,398.

To all whom it may concern:

Be it known that I, DAVID F. LAING a subject of the King of England, residing at McDonald Hills, in the Province of Saskatchewan and Dominion of Canada, have invented new and useful Improvements in Swingletree-Clips, of which the following is a specification.

The purpose of the invention is to provide a swing tree clip which will not work loose on the swing tree on which it is attached when the latter dries out and thereby contracts. To this end the invention, made very much like the usual clip, is provided with laterally extended ears each of which is formed with a boss set in a counterbored portion of the swing tree, so that as the latter contracts, thus reducing its cross-sectional dimensions so that the clip would otherwise become loose, this contraction may effect a tight hugging of the bosses, thereby holding the clip firmly in position.

To the exact construction in which it is shown and described, the invention is not to be restricted. The right is reserved to make such changes or alterations as the actual reduction to practice may suggest, in so far as such changes or alterations are comprehended in spirit by the annexed claim.

In the accompanying drawings:

Figure 1 is a perspective view of the end of a swing tree showing the improved clip attached thereto.

Fig. 2 is a longitudinal section of the structure of Fig. 1.

Fig. 3 is an elevational view of the clip detached from the swing tree and looking in the opposite direction as viewed in Fig. 1.

Referring to the drawings, there is shown one end of a swing tree 1, the improved clip B being attached at the extremity of this end. The improved clip comprises the usual band 2 in surrounding relation to the swing tree and carrying the usual hook 3 provided for the attachment of the trace. The band 2 further than carrying the hook 3 is provided on diametrically opposite sides with the lat-

erally extending ears 4, each carrying a boss 5, so that the two bosses face each other. In the attachment of the band 2 to the swing tree, the latter is counterbored to provide pockets in which the bosses 5 may rest. The whole is further secured to the swing tree by a bolt 6 passing through appropriate holes formed in the ears 4 and bosses 5 and a transverse hole formed in the swing tree 1 in alinement with the aforesaid hole.

So long as the swing tree 1 maintains its normal size, the band 2 will hug it tightly, but should the swing tree shrink, as is likely to be the case in very dry weather, the band 2 cannot hug the swing tree so tightly and would, therefore, but loosely engage the swing tree, were not the bosses 5 provided. These bosses 5 set in the counterbored portions are tightly hugged by the circular walls of the counterbored portion when the swing tree shrinks and, therefore, the band 2 is held in tight engagement with the swing tree despite the shrinkage or contraction thereof.

In attaching the improved clip to a swing tree, the two ears 4 may be bent outwardly with reference to the band 2, so that the bosses 5 may not interfere with the attachment of the band, the arms 4 being bent back in place when the bosses engage in the counterbored portions and the bolt 6 is attached.

The invention having been described, what is claimed as new and useful is:

The combination with a swing tree formed with counterbores on diametrically opposite sides and inset from its end, of a clip attached to the swing-tree in surrounding relation to the end portion of the latter and provided with trace attaching means and formed with laterally projecting ears overlying the counterbores and formed with bosses disposed in the counterbores, and a bolt passing through the ears, through the bosses and through the swing-tree.

In testimony whereof I affix my signature.
DAVID F. LAING.
